UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

ENVELOP.

1,371,332.

Specification of Letters Patent. Patented Mar. 15, 1921.

Application filed June 25, 1919. Serial No. 306,642.

To all whom it may concern:

Be it known that I, WILLARD E. SWIFT, a citizen of the United States, residing at Worcester, in the county of Worcester and 5 Commonwealth of Massachusetts, have invented a new and useful Improvement in Envelops, of which the following, together with the accompanying drawings, is a specification.

10 My present invention relates to that class of envelops which are provided with a loose or removable flap which entitles them to pass through the mail at a reduced rate, such envelops sometimes being known as "penny 15 saver" envelops.

In the accompanying drawings,

Figure 1 represents an envelop having its seal flap closed and a removable flap withdrawn from the end of the envelop.

20 Fig. 2 represents the blank from which the envelop is made.

Fig. 3 represents the blank with the side flaps folded, with gum applied thereto and also to the seal flap.

25 Similar reference characters refer to similar parts in the different figures.

Referring to Fig. 2, which represents the blank from which the envelop is made, 1 denotes the rectangular body portion of the 30 envelop, 2 denotes the back flap, 3 the seal flap, 4 a narrow side flap at one end of the body portion, 5 a wider side flap at the opposite end of the envelop, and 6 a removable flap to allow the inclosure in the envelop to 35 be inspected.

In forming the envelop from the blank represented in Fig. 2, the side flaps 4, 5 and 6 are folded on the broken lines 7, 8 and 9, as represented in Fig. 3. Gum is applied 40 to the seal flap at 10, to the surface of the side flap 4 as represented at 11, Fig. 3, and also at 12 to the side flap 5. The back flap 2 is then folded on the broken line 13, and the seal flap 3 is creased on the broken line 45 14.

The side flap 6 is cut away at 15 on an oblique line to expose a portion of the back flap 2, so that when the back flap is folded on the broken line 13 the gummed surface 12 on the side flap 5 will be brought into contact with the back flap 2 in the space indicated by the broken line 16.

When the envelop is completed the edge of the back flap 2 will adhere to the gummed surface 11 of the side flap 4, and the back flap 2 will also be brought into contact with 55 the spot of gum 12 on the side flap 5, causing the back flap to adhere to the side flaps 4 and 5, leaving the flap 6 unattached and capable of being withdrawn from the end of the envelop into the position shown by 60 the broken lines 17, Fig. 1. When the envelop is completed an inclosure may be inserted, and the seal flap 3 turned over and attached to the back flap by its gummed surface 10, as represented in Fig. 1. 65

The side flap 6 when folded is in alignment with side flap 5, as shown in Fig. 3, but is separated therefrom by an oblique incision 18, having a portion of the side flap 5 overlapping the back flap 2. When the 70 back flap is folded on the broken line 13, the fold extends across the side flap 5. The side flaps 4 and 5 when the back flap 2 has been folded will include the inclosure and prevent it from accidental displacement, 75 when the removable flap 6 has been withdrawn into the position shown by the broken lines 17, Fig. 1.

I claim,

1. An envelop comprising a rectangular 80 body portion, a gummed seal flap, a back flap, a side flap folded upon one end of said body portion, adhesive material applied to the exposed surface of said side flap, a second side flap folded upon the opposite end 85 of said body portion, with one end overlapping said back flap, an adhesive material applied to a restricted area of said second side flap, and a removable ungummed flap folded upon said back flap, having a portion 90 cut away to expose a portion of the back flap alining with the adhesive material on said second side flap, with said back flap folded upon and attached to the adhesive surfaces of said side flaps. 95

2. An envelop formed from a blank having a body portion, a seal flap projecting from one edge of said body portion, a back flap projecting from the opposite edge of said body portion, a side flap projecting 100 from said body portion, a second side flap projecting from the body portion and from

a portion of said back flap, and a third flap projecting from the back flap in alinement with said second side flap and having a portion removed to expose a portion of the 5 back flap to contact with said second side flap, adhesive material applied to said seal flap and to the contacting surfaces of the

side flaps with the back flap when the flaps are folded upon the body portion.

Dated this 16th day of June, 1919.

WILLARD E. SWIFT.
